(57) **CLAIM**

The ornamental design for a portion of a hand tool, as shown and described.

DESCRIPTION

FIG. 1 is a perspective view of a portion of a hand tool according to our new design;

FIG. 2 is a left side elevation view thereof;

FIG. 3 is a right side elevation view thereof;

FIG. 4 is a top plan view thereof;

FIG. 5 is a bottom plan view thereto;

FIG. 6 is a front elevation view thereof;

FIG. 7 is a perspective view thereof, shown in the environment of a complete hand tool, shown in an open configuration;

FIG. 8 is a right side elevation view thereof;

FIG. 9 is a left side elevation view thereof;

FIG. 10 is a rear elevation view thereof;

FIG. 11 is a front elevation view thereof;

FIG. 12 is a bottom plan view thereof;

FIG. 13 is a top plan view thereof; and,

FIG. 14 is a right side elevation view thereof, shown in the environment of a complete hand tool, shown in a closed configuration.

The broken lines shown in the drawings represent unclaimed portions of the hand tool that form no part of the claimed design.
